(57) **CLAIM**

The ornamental design for a handle for juice and milk cartons, as shown and described.

DESCRIPTION

FIG. 1 is a perspective view of a handle for juice and milk cartons showing my new design;

FIG. 2 is a front elevational view thereof;

FIG. 3 is a left side elevational view thereof, the right side elevational view being a mirror image thereof;

FIG. 4 is a top elevational view thereof;

FIG. 5 is a rear elevational view thereof;

FIG. 6 is a bottom elevational view thereof; and,

FIG. 7 is a perspective view showing the handle for juice and milk cartons in use; the broken lines depict environmental structure for illustrative purposes only and form no part of the claimed design.

1 Claim, 4 Drawing Sheets

FIG. 1.

FIG. 2.

FIG. 3.

FIG. 4.

FIG.5.

FIG.6.

FIG. 7.
